HOLDER FOR A BABY NURSING BOTTLE OR THE LIKE

Ralph J. Rutledge, Sr., Charleston, W. Va.

Application January 23, 1959, Serial No. 54,282

Term of patent 14 years

(Cl. D83—8)

FIG. 3

I claim:

The ornamental design for a holder for a baby nursing bottle or the like, as shown.
